Des. 2326

Samuel H. Flesheim, of Chicago, Ill.
Letters Patent No. 2326 Dated May 29, 1866.
Design for a Trade Mark for Lead Pencils.

The schedule referred to in these Letters Patent and making part of the same,

To all whom it may concern:

Be it known that I, Samuel H. Flesheim, of Chicago, in the county of Cook, and state of Illinois, have invented and produced a new and ornamental Design to be stamped or impressed upon Lead Pencils; and I do hereby declare that the following is a full, clear and exact description of the same, reference being had to the accompanying drawings, which form part of this specification.

The invention of any said Design consists in stamping or impressing or printing in any suitable manner upon a lead pencil the word "Bremen"; and also the figure shown in the drawings consisting of two flags, arranged as represented, having between them a field of stars and at the intersections of the flag staffs a number of intersecting arrows, substantially as shown in the said drawings, the whole forming a distinctive and ornamental Design or Trade mark for Lead Pencils.

What I claim and desire to secure by Letters Patent, is A design for a trade mark for Lead Pencils substantially as herein shown and described.
